UNITED STATES PATENT OFFICE

EUGEN HINDERER, OF HAMBORN, GERMANY, ASSIGNOR TO VEREINIGTE STAHLWERKE AKTIENGESELLSCHAFT, OF DUSSELDORF, GERMANY, A CORPORATION OF GERMANY

MEANS FOR SEPARATING ADHERING ROLLED METAL SHEETS

Application filed January 7, 1927, Serial No. 159,735, and in Germany August 19, 1926.

In rolling mills for metal sheets, a large number of the latter becomes useless by the fact that the rolled, at least double metal sheets adhere so fast to one another that they 5 cannot be separated but with extremely great difficulty, which is further increased if the metal sheets are at some places welded to one another.

The present invention provides improved 10 means for effecting said separation in a mechanical way, by pulling said sheets over a contrivance engaging between said sheets and receiving a rocking or (and) rotary motion, said contrivance consisting preferably of one 15 or more cutterlike bodies of suitable cross-section, eventually in combination and co-acting with stationary cutters, and which, if consisting of a pair of cutters, are driven to receive a rocking motion like that of the two 20 members of a pair of tongs; the introduction of the metal sheets into the device for pulling the same over the separating contrivance being effected by means of splitting magnets and intermediary guides.

25 The accompanying drawings illustrate how the invention can be put into practice:—

Figs. 1 and 2 show, by way of example, a side view and a fragmentary plan view respectively of a preferred constructional form 30 of an apparatus for effecting the separation of the adhering metal sheets; Figs. 3 and 4 are cross-sections, respectively on the lines 3—3 and 4—4 of Fig. 2; and Figs. 5 to 14 are diagrammatical cross-sections through various forms of the movable separating contrivance and of the metal sheets during their movement over the latter.

Referring to Figs. 1 to 4 inclusive:—

The adhering rolled metal sheets are first 40 split open at their front ends and with the joint thus formed placed over the separating contrivance consisting, for instance, of a pair of cutters *a* receiving a rocking motion like that of the members of a pair of tongs. Behind 45 said contrivance the two metal sheets are caught by tongs *b* which pull the same over said contrivance by means of cords *c* wound on a drum *d* connected with an electromotor *f* by means of a toothed gear *e*. 50 Another motor *g* effects the rocking motion

of the pair of cutters by means of eccentrics *h* on its shaft, which are connected by rods *i* to links *k* attached to the turning-pivots of the cutters.

By the combined movement of the metal 55 sheets over said separating contrivance, and the rocking motion of the cutters of the latter, the metal sheets are gradually separated from one another with absolute safety.

The cutter- or roller-shaped bodies may be 60 constructed as follows:—

Fig. 5 shows a pair of rocking cutters *a* in the two end positions of its rocking motions (see full-line and dotted-line positions of the same). 65

Fig. 6 shows one rotary round body.

Fig. 7 shows one wedge-shaped cutter only performing a rocking motion (see full-line and dotted-line positions of the same).

Fig. 8 shows a rocking or rotary body of 70 square cross-section.

Fig. 10 shows a pair of round bodies rotating in opposite directions.

Fig. 11 shows a rotary round body in combination and co-acting with an immovable 75 cutter.

Fig. 12 shows a rotary round body in combination and co-acting with a rocking cutter.

Fig. 13 shows a rotary body in combination with two pairs of wedge-shaped cutters for separating four superposed adhering metal sheets rolled in common. 80

The initial separation of the metal sheets at their front ends, for obtaining the joint 85 with which they are placed over the separating contrivance, can be effected either by hand, or, as this is rather cumbersome and time-wasting, preferably also by a mechanical contrivance such as for instance illustrated in Fig. 9.

The two rolls *l* therein lead the metal sheets first between two magnets *m* whereby the sheets are split open at their front ends and then passed along guides *n* over the separating contrivance *a* and caught by the tongs *b*, the guides and magnets being then removed and the sheets normally moved over the separating contrivance by the pulling cords *c*. 95 100

Fig. 14 shows the arrangement of the two magnets m^1 within the rolls l .

I am aware that it has been proposed to separate adhering rolled metal sheets by means of an immovable spreader bar engaging between the same during their advance, and I distinctly disclaim any use of the said known means separately.

What I claim, is:—

- 10 1. An apparatus for separating adhering rolled metal sheets comprising in combination a device engaging between the sheets to be separated, means for pulling the sheets over said device, means for imparting to said device a separating motion during the travel of the sheets over the device, and immovable cutters coacting with said movable separating device.
- 15 2. An apparatus for separating adhering rolled metal sheets comprising in combination a device engaging between the sheets to be separated and consisting of a pair of cutters, means for pulling the sheets over said device, and means for imparting to said pair of cutters a tong-like rocking motion.
- 20 3. An apparatus for separating adhering rolled metal sheets comprising in combination a separating device engaging between the sheets to be separated, means for imparting an oscillating movement to said device, a drum, cables adapted to be wound on the drum, and means for attaching the front edges of the metal sheets to the cables.
- 25 4. In an apparatus for separating adhering rolled metal sheets, a separating device comprising a pair of cutters journalled in the frame of the apparatus, and means for imparting to the cutters a rocking motion like that of the two members of a pair of tongs.
- 30 40 In testimony whereof I have hereunto set my hand.

EUGEN HINDERER.
